US00D750810S

(12) **United States Design Patent**
Buzza

(10) **Patent No.:** **US D750,810 S**
(45) **Date of Patent:** **** Mar. 1, 2016**

(54) **SHINGLE**

(71) **Applicant:** **Building Materials Investment Corporation**, Dallas, TX (US)

(72) **Inventor:** **Stephen A. Buzza**, Newburgh, IN (US)

(73) **Assignee:** **Building Materials Investment Corporation**, Dallas, TX (US)

(**) **Term:** **14 Years**

(21) **Appl. No.:** **29/489,541**

(22) **Filed:** **Apr. 30, 2014**

(51) **LOC (10) Cl.** **25-01**

(52) **U.S. Cl.**

USPC **D25/139**

(58) **Field of Classification Search**

USPC **D25/139**

CPC **E04D 1/00; E04D 2001/005; E04D 1/26**

See application file for complete search history.

OTHER PUBLICATIONS

Information Disclosure Statement submitted in U.S. Appl. No. 10/777,950, now U.S. Pat. No. 7,805,905, on May 24, 2010 (7 pages).

Primary Examiner — Doris Clark

(74) *Attorney, Agent, or Firm* — Fitzpatrick, Cella, Harper & Scinto

(57) **CLAIM**

The ornamental design for a shingle, as shown and described.

DESCRIPTION

FIG. 1 is a top plan view of a first embodiment of my design; FIG. 2 is a top plan view of a second embodiment of my design;

FIG. 3 is a top plan view of a third embodiment of my design; FIG. 4 is a top plan view of a fourth embodiment of my design;

FIG. 5 is a top plan view of a fifth embodiment of my design;

FIG. 6 is a top plan view of a sixth embodiment of my design;

FIG. 7 is a top plan view of a seventh embodiment of my design;

FIG. 8 is a top plan view of an eighth embodiment of my design;

FIG. 9 is a top plan view of a ninth embodiment of my design;

FIG. 10 is a top plan view of a tenth embodiment of my design;

FIG. 11 is a top plan view of an eleventh embodiment of my design;

FIG. 12 is a top plan view of a twelfth embodiment of my design;

FIG. 13 is a top plan view of a thirteenth embodiment of my design;

FIG. 14 is a top plan view of a fourteenth embodiment of my design;

FIG. 15 is a right side view of the embodiments of FIGS. 1-14;

FIG. 16 is a front elevation view of the embodiment of FIG. 1;

FIG. 17 is a front elevation view of the embodiment of FIG. 2;

FIG. 18 is a front elevation view of the embodiment of FIG. 3;

FIG. 19 is a front elevation view of the embodiment of FIG. 4;

FIG. 20 is a front elevation view of the embodiment of FIG. 5;

FIG. 21 is a front elevation view of the embodiment of FIG. 6;

FIG. 22 is a front elevation view of the embodiment of FIG. 7;

FIG. 23 is a front elevation view of the embodiment of FIG. 8;

FIG. 24 is a front elevation view of the embodiment of FIG. 9;

FIG. 25 is a front elevation view of the embodiment of FIG. 10;

FIG. 26 is a front elevation view of the embodiment of FIG. 11;

FIG. 27 is a front elevation view of the embodiment of FIG. 12;

FIG. 28 is a front elevation view of the embodiment of FIG. 13;

FIG. 29 is a front elevation view of the embodiment of FIG. 14;

FIG. 30 is a rear elevation view of the embodiments of FIGS. 1-14; and,

FIG. 31 is a bottom plan view of the embodiments of FIGS. 1-14.
